UNITED STATES PATENT OFFICE.

EMMANUEL EASTWOOD, 2d, OF PROVIDENCE, RHODE ISLAND.

BELT-FASTENER.

SPECIFICATION forming part of Letters Patent No. 391,695, dated October 23, 1888.

Application filed June 14, 1888. Serial No. 277,060. (No model.)

To all whom it may concern:

Be it known that I, EMMANUEL EASTWOOD, 2d, a citizen of the United States, residing at Providence, in the county of Providence and 5 State of Rhode Island, have invented certain new and useful Improvements in Belt-Fasteners; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 My invention relates to belt fasteners or couplings, the same being more especially adapted to be used with round belts; and it consists, essentially, of a metallic sleeve or socket-piece having one or more integrally-formed 20 arms provided each at its free end with a penetrating-lug, the latter adapted to pass through an incision formed in the shell of the coupling and into the leather or material composing the belt, all as will be more fully hereinafter set 25 forth and claimed.

The object of my invention is to cheapen the cost of the class of belt-fasteners referred to, which usually, heretofore, have been secured to the belt by screw-threading, and 30 sometimes by swaging or pinching the metallic shell, thereby reducing its diameter to more securely retain the ends of the inclosed belt. Another advantage resulting from my improvement is that the belt is more firmly 35 fastened to the coupling by reason of the penetrating prongs or lugs. The belt may be readily detached from the coupling by simply raising the free end of the lug-carrying arm.

In the accompanying drawings, Figure 1 40 represents the ends of a round belt coupled together by means of my improved fastening, a portion of the belt and coupling being in section. Fig. 2 is a perspective view of a hook-coupling, each piece thereof having my 45 improved holding device. Fig. 3 is a modified form of the coupling shown in Fig. 1. Fig. 4 is a cross-sectional view taken on line $\alpha\alpha$ of Fig. 3, showing the holding-prong inserted into the belt. Fig. 5 is a perspective 50 view of a hook-coupling, each half having a single arm. Fig. 6 is a detached side view of one-half of a hook-coupling, showing the

prong-carrying arms bent back to permit the entrance of an end of a belt; and Fig. 7 is an end view thereof.

55

The construction, arrangement, and operation of my improved belt-coupling are as follows:

a, referring to the drawings, designates a round belt, made of leather, rubber, or other 60 flexible material, as usual in belts of this class.

a indicates my improved coupling or belt fastening, the same consisting of the shell *c*, having one or more integrally-formed arms, *d*, extending throughout a portion of its length, 65 as clearly shown. An elongated opening, *d'*, is cut through the shell adjacent to each of said arms, the shape of the slot and arms being such that when the latter are bent down, as in use, the whole presents a substantially cylindrical 70 form. The free end of each arm is provided on its under side with a spur or penetrating-prong, *e*, adapted to pierce the belt. In some forms the coupling consists of two parts, the contiguous ends thereof being linked together 75 by hooks *b*, as clearly represented by Figs. 2, 5, and 6. The opposite or belt-receiving ends of the coupling are provided with the spur-arms *d*, as before described with reference to the fastener shown by Figs. 1 and 3.

80

In Fig. 1 the coupling is continuous, and is provided with a center tie, *m*, to which the spur-arms are united at each side. In Fig. 3, however, the tie is omitted, and the arms *d* are reversely arranged—that is to say, the spur or free end of one arm is opposed by the connected end portion of the other arm. The dotted lines in the several figures indicate the position of the spur-arms prior to the insertion of the belt.

90

The manner of connecting the belt by means of my improved coupling is as follows: An end of the belt is reduced slightly, as at *a'*, and then forced into an end of the coupling's shell to the desired depth, (the arms *d* meanwhile being in the position shown by Fig. 6,) after which the arm or arms are forced down into the recess *d'*, thereby at the same time causing the spurs *e* to penetrate the adjacent end portion of the belt, the operation being next repeated upon the other half of the coupling. The belt is practically made endless by the use of the coupling shown in Figs. 1 and 3, the ends of the belt being reduced and forced

95

100

into the respective ends of the coupling's shell and the arms next bent down, thereby inserting the spurs *e* into the belt, as before described.

My improved fastening may be made of brass or malleable iron, or it may be produced by the process of drop-forging.

I claim as my invention—

1. The improved coupling for round belts hereinbefore described, consisting of an apertured shell having integrally-formed arms provided with spurs or prongs, constructed and arranged whereby the act of bending the arms downwardly causes the prongs to penetrate the belt, substantially as shown and described.

15. 2. The belt-coupling hereinbefore described, consisting of the two apertured socket portions having means, substantially as described,

for coupling them together, each of said portions having one or more integrally-connected spur carrying arms provided with spurs or prongs, substantially as and for the purpose set forth.

3. The belt-coupling hereinbefore described, having its shell *c* adapted to receive the two ends of the belt, and provided with integrally-formed spur-carrying arms *d*, spurs *e*, and incisions *d'*, substantially as shown, and for the purpose set forth. 25

In testimony whereof I have affixed my signature in presence of two witnesses.

EMMANUEL EASTWOOD, 2d.
